The ornamental design for a multi-sump grease containment apparatus, as shown and described.

DESCRIPTION

FIG. 1 is a perspective view of a multi-sump grease containment apparatus according to a first embodiment showing my new design;

FIG. 2 is a rear elevation view thereof;

FIG. 3 is a front elevation view thereof;

FIG. 4 is a top plan view thereof;

FIG. 5 is a bottom plan view thereof;

FIG. 6 is a right side elevation view thereof;

FIG. 7 is a left side elevation view thereof;

FIG. 8 is a perspective view of a multi-sump grease containment apparatus according to a second embodiment showing my new design;

FIG. 9 is a rear elevation view thereof;

FIG. 10 is a front elevation view thereof;

FIG. 11 is a top plan view thereof;

FIG. 12 is a bottom plan view thereof;

FIG. 13 is a right side elevation view thereof; and,

FIG. 14 is a left side elevation view thereof.

All features shown in broken lines are not part of the design sought to be patented.
